United States Patent Office.

HIRAM H. SCOVILLE, OF CHICAGO, ILLINOIS.

Letters Patent No. 78,332, dated May 26, 1868.

IMPROVED STONE-BREAKER.

The Schedule referred to in these Letters Patent and making part of the same.

Be it known that I, HIRAM H. SCOVILLE, of the city of Chicago, and State of Illinois, have invented a new and useful Machine for Breaking Stone.

The invention consists in constructing a machine, with a fixed column in the centre of the machine, (it being of the same piece, and part of the bed,) together with a hopper oscillating on trunnions, upon each side of the column. I also face the opposite sides of the column with concave plates, corrugated transversely, and the opposite ends of the hopper with convex plates, corrugated in the same manner. Said plates are attached to the column and hopper by caps, or in any other manner convenient for removal.

The shape of the corrugated surfaces on the column and hopper may be changed from the above description, so as to make the column convex, and the hopper concave, or the corrugations may be made vertical instead of horizontal; but I prefer the mode of construction first above described, as the best.

To enable others to construct and operate a machine like mine, I will describe the same in detail, and I hereby declare the following to be a full, clear, and exact description of the construction of the machine, reference being had to the annexed drawings, making a part of this specification, in which—

Figure 1 is a view of the top of the machine.

Figure 2 is a longitudinal elevation.

The several parts are described as follows, to wit: The part represented by the letter A is the bed of the machine. B is one of the trunnions upon the column C, upon which the hopper D oscillates. E E are convex plates, transversely corrugated, attached to each end of the hopper D. F F are concave plates, transversely corrugated, attached to opposite sides of the column C.

G is a driving-pulley. H is a shaft, on which is an eccentric or crank. K is a connecting-rod, connecting, by the pin L, the shaft H to the hopper D. M M M are caps holding in place the plates E E and F F.

Having described the several parts that are essential to the practical operation of the machine, I will now describe the operation of breaking stone. Power being applied to the pulley G, the shaft H is made to revolve, and through the medium of the eccentric and connecting-rod, a rocking or oscillating motion is given to the hopper D. Power being applied to the hopper at L, from a point approximating a vertical line with the pin L, each revolution of the shaft H causes the ends of the hopper D to approach and recede from the column C, causing in effect a double-acting breaker.

What I claim as my invention, and desire to secure by Letters Patent, is—

The fixed central column C, with its corrugated faces, in combination with the corrugated faces on the oscillating hopper D, the arm K, the shaft H, with its eccentric or crank, all arranged and operating substantially as herein described.
